MINING MACHINE.
APPLICATION FILED AUG. 22, 1902.

2 SHEETS—SHEET 2.

UNITED STATES PATENT OFFICE.

EDWIN R. MERRILL, OF COLUMBUS, OHIO, ASSIGNOR TO JOSEPH A. JEFFREY, OF COLUMBUS, OHIO.

MINING-MACHINE.

No. 813,508.

Specification of Letters Patent.

Patented Feb. 27, 1906.

Application filed August 22, 1902. Serial No. 120,680.

To all whom it may concern:

Be it known that I, EDWIN R. MERRILL, a citizen of the United States, residing at Columbus, in the county of Franklin and State 5 of Ohio, have invented certain new and useful Improvements in Mining-Machines, of which the following is a specification, reference being had therein to the accompanying drawings.

Figure 1 is a plan view, some of the parts 10 being broken away, showing a mining-machine embodying my improvement. Fig. 2 is a vertical section on the line 2 2, Fig. 1. Fig. 3 is a front view of the motor and engine and showing also parts of the carriage and of 15 the bed in section. Fig. 4 is a bottom plan view of the engine and motor.

The machine considered as a whole is similar 20 to those heretofore in use in having a bed-frame and a carriage sliding thereon for supporting the cutting apparatus and the power mechanism.

The bed consists of longitudinal side bars A A, supported at intervals by cross-girders a, having upright arms a', which are secured 25 to the main bars A. At the bottoms and along the sides these cross-bars a are provided with longitudinal shoe-like bars a''. At the front end there is a bottom cross-bar a'', which is longer than those at a a and which 30 permits the rear part of the bed to be narrow and yet allows the use of a cutting apparatus which is wide at its front end.

At the rear end the bed is provided with a 35 cross-bar a'', which not only serves to hold the parts together, but also provides means for moving the machine, as bars or other tools can be readily engaged therewith.

The bed-bars A have secured to them longitudinally-arranged rack-bars B with up- 40 wardly-turned teeth.

Upon the bed-frame of this construction is mounted the traveling apparatus, which carries the cutting devices and also the gearing and motor or engine. This carriage is made 45 up of two main parts, the platform or frame, which supports the gearing, shafting, and motor or engine, and the cutter-frame. The cutter-frame is designed for the holding and guiding of a chain provided with cutters and 50 may be of any preferred sort. The one shown comprises a front cross-head C, a central thrusting frame or bar C', and tapering side guide-bars C'', converging rearward toward the center bar or frame C'. The cross-

head C is formed of top and bottom plates c 55 c', with spacing bars or plates between them, together with sprocket-wheels C³ C⁴. One of the spacing bars or plates of the cross-head C has rearwardly-projecting arms C⁵, to which is secured the central thrusting device C'. 60 This consists of two longitudinal bars c² c², which are riveted or otherwise secured to the arms C⁵ of the cross-head and which extend back to points near the rear of the machine. They are held spaced and braced by means of 65 a cross-plate c³, which has vertical flanges c⁴, that permit it to be firmly riveted to the bars c². The front end of the bar or plate c³ is adjacent to the rearward-extending arms C⁵ of the cross-head, and it extends back to points 70 somewhat ahead of the rear ends of the bars c². At the said rear ends there is a plate or bar C⁶. At its rear the thrusting member C is provided with the cross members c⁶ c⁷, which are adapted to support the adjusting- 75 screw D, which is used to take up slack in the cutter-chain by moving the rear cutter-chain sprocket relative to the thrusting member C in the well-known manner.

The rear end of this chain-frame is adjust- 80 ably connected to the platform, frame, or support for the shafting and gearing. This support or frame consists, as shown, of a plate having a horizontal part E, which is fitted to the bed to slide longitudinally thereon, it 85 having at the front end the drooping part e and a supplemental drooping portion e', together with a rear portion e'', having projections e³.

The above-described chain-frame has its 90 rear end between the drooping parts e and e' of the motor-frame. It is held by means of a vertical bar or rod F, provided with a threaded aperture to receive the above-mentioned screw D. This rod F is detachable from the 95 engine-plate, though normally rigidly secured thereon, it being seated in apertures in the parts e e'. It has a clamping washer and nut at the upper end and a head at the lower end, so that it can be loosened when desired 100 or can be fastened with the utmost rigidity. It is preferably cylindrical or adapted to turn somewhat, so that in case of great strain upon the screw-rod there can be a yielding.

When it is desired to adjust the chain-frame forward relatively to the motor-frame, this is accomplished after first loosening the vertical rod F and then turning the screw-rod 105

D in the proper direction, and after adjustment the vertical rod F is again clamped in position.

The machine is driven by means of a motor or engine adapted to be actuated by a fluid agent, preferably compressed air. This motor comprises a casing having the two parts H H² each nearly cylindrical in shape and the intermediate smaller part - cylindrical walls at g³ g⁴. The vertical walls of the outer cylindrical parts are represented by g² and the bottom plate or wall by g', these being preferably cast integral. At the center of each of the circular sections of the bottom wall 15 there is a bearing-boss h, which projects downward. In each of the side cylindrical parts H H² of the casing there is mounted a vertical shaft H', each shaft being journaled at its lower end in one of the bearing-bosses 20 h. The cover or top wall of the casing g is preferably detachable from the lower part of the casing, though secured thereto tightly by bolts g⁵. This top wall g has bearing-bosses g⁶, one for each of the shafts H'. Each shaft 25 H' has secured to it a cylindrical piston-carrier H³, the piston-plate itself being illustrated at H⁴.

In the central part of the casing there is mounted a valve cylinder or roll H⁵. This 30 roll is carried by the shaft h⁵, which is mounted at its lower end in the boss or bearing h⁶ in the bottom wall or plate g'. It has a cut-out portion h', adapted to register with each of the piston-plates H⁴ alternately. At h² there 35 is an inlet-port for compressed air or steam, and at h³ there is an exhaust-port, there being one of these inlet and exhaust ports for each of the cylindrical parts H H². At the lower end of each of the shafts H' and rigidly 40 fastened thereto is a spur-pinion K. These engage with the large spur-wheel L, mounted on the vertical shaft l, held in boxes carried by suitable brackets secured to the platform or frame of the motor and gearing. The pinions K both being of the same size it will be 45 seen that they not only impart the same power and speed to the large gear L, but also that they are so connected as to cause the cylinders or rollers H³ to rotate together and 50 in the same direction.

The valve cylinder or roller H⁵ is connected with the shafts H' by means of the gear-wheels H⁶ H⁷, so that the valve also rotates synchronously with the piston parts.

55 With a driving mechanism of the character described I am enabled to impart motion to the master-gear L, the chain-wheel M, and the other parts driven thereby with much less gearing and fewer parts and less metal than 60 have been required in machines of this class heretofore.

From the shaft l can be taken the power for moving the carriage forward and back.

The entire carriage can be simultaneously 65 advanced along the bed as follows: O O are

pinions engaging with the racks B above described. These pinions are rigid with the shaft P, which is mounted in bearings at p in the platform or frame extension e³. This shaft can be rotated slowly in one direction 70 or rapidly in the opposite direction. Q is a worm on the aforesaid shaft l. It engages with a worm-wheel Q' upon a shaft q, which is mounted in suitable bearings upon the engine-platform. This shaft q has a beveled 75 gear-wheel Q⁴, which engages a bevel-wheel Q⁵ on a longitudinally-arranged shaft q' in a bracket-bearing q². This shaft q' carries a worm Q², which engages with the worm-wheel Q³, mounted loosely on the shaft P. The 80 aforesaid shaft q carries also a gear-pinion R, which engages with a gear-wheel R³, also mounted loosely on shaft P. The wheels Q³ and R³ can be alternately connected to the shaft P by the clutch S, which is feathered or 85 splined to the shaft. When the clutch engages with the wheel Q³, the speeds and directions of the parts are such that the carriage is slowly advanced. When the clutch is withdrawn from the wheel Q³ and engaged 90 with wheel R³, the carriage is rapidly withdrawn along the bed, the wheel Q³ moving in one direction with a relatively slow speed, while the wheel R³ moves in the opposite direction with a relatively high speed. 95 With this clutch can be combined any suitable mechanism for moving it automatically or for moving it by hand, or both. In my earlier application, Serial No. 25,811, filed August 3, 1900, I have shown a mechanism 100 which can be employed for this purpose. The lever S', pivoted to the platform E or a suitable support thereon and having parts engaging with the clutch, can be used, as readily understood. Compressed air is admitted to 105 the motor through the inlet-ports at h² from a hose or flexible conductor, which is attached at T or T'. It travels past the valve at t to the passage-way at t', then along the duct t' until it reaches the inlet-port h². As the piston-carrier H³ turns it brings its air passage-way V to the port h² and air passes through 110 the carriage or roll from the bottom to the top and escapes through the ports v into the cylinder behind the piston-plates H⁴ and causes the rotation of the parts H³ and the shafts H'. As soon as the plate H⁴ reaches the intermediate roll H⁵ the recess h' in the latter permits the passage of the said part 115 H⁶, and the latter escapes from the roll H⁵ just as the cylindrical surfaces of the parts H⁴ and H⁵ come into contact again and just as it reaches the inlet-port h². The plate H⁴ begins to enter the recess h' just after it has 120 passed the exhaust-port h³. The two sets of parts (each set having a roll H³, a shaft H', and an external cylinder, &c.) are arranged 125 oppositely to each other with respect to the intermediate roll H⁵, so that the motor is practically a double-acting one, maintaining 130

substantially continuous application of power to the gearing and through that to the cutters and the carriage-moving mechanism.

What I claim is—

5. 1. In a mining-machine, the combination with the bed-frame, the carriage adapted to move forward and back thereon, and the cutting apparatus on the carriage, of the two rotary engines arranged side by side within the 10 longitudinal planes of the bed-frame, and having the axes of their engine-shafts in a vertical plane transverse to the said bed-frame, the vertical shaft *l*, the gearing between said shaft and each of said engine-shafts, the 15 sprocket-wheel on said vertical shaft engaging with and driving the cutter-chain, and a train of power-transmitting devices interposed between said vertical shaft and the carriage-advancing mechanism on the bed-frame.
2. In a mining-machine, the combination with the bed, the carriage adapted to move relatively thereto and the cutter-chain on the carriage, of the sprocket-wheel engaging with 25 and driving the said chain, the vertical shaft *l* to which the sprocket is secured, the worm on said shaft for transmitting power to the carriage-advancing mechanism, the gear-wheel on said shaft, and the two vertical engineshaft having their axes of rotation in a 30 plane transverse to the carriage-frame and in front of the said driving sprocket-wheel, the casings of said motors being arranged within the longitudinal planes of the sides of said bed-frame, the rotary pistons connected with and rotating said shafts and driving-pinions 35 on said shafts engaging with and driving said gear-wheel *l* on the sprocket-shaft, substantially as set forth.
40. 3. In a mining-machine, the combination of the bed-frame, a carriage-frame adapted to move forward and back thereon, an endless cutter-chain on the carriage-frame, two rotary elastic-fluid engines arranged side by side on the carriage-frame and having the 45 axes of their rotary-engine shafts in a vertical plane transverse to the said carriage-
- frame, and power-transmitting mechanism interposed between said rotary-engine shafts and both the cutter-chain and the bed-frame 50 and adapted both to actuate the said cutter-chain and to cause the carriage to move forward and back along the said bed-frame.
4. In a mining-machine, the combination with the bed-frame, the carriage-frame adapted to move forward and back thereon, and the endless cutter-carrier on the carriage-frame, of two rotary elastic-fluid engines arranged side by side on the carriage-frame and having the axes of their rotary-engine shafts 60 in a vertical plane transverse to the said carriage-frame, a vertical counter-shaft common to both of said engine-shafts, gearing similarly connecting each of said rotary-engine shafts to said counter-shaft, power-transmitting mechanism interposed between said counter-shaft and said cutter-carrier, and power-transmitting mechanism interposed between said counter-shaft and said bed-frame adapted to cause the carriage to move 70 forward and back along the said bed-frame.
5. In a mining-machine, the combination with a bed-frame, a carriage-frame arranged to move forward and back thereon and an endless cutter-carrier on the carriage-frame, 75 of two rotary elastic-fluid engines arranged side by side on the carriage-frame and having the axes of their rotary-engine shafts parallel with each other, a counter-shaft common to both of said engines, gearing similarly connecting each of said rotary-engine shafts to said counter-shaft, power-transmitting mechanism interposed between said counter-shaft and said cutter-carrier, and power-transmitting mechanism interposed between said 80 counter-shaft and said bed-frame and adapted to cause the said carriage to move forward and back along said bed-frame.

In testimony whereof I affix my signature in presence of two witnesses.

EDWIN R. MERRILL.
